CIRCUIT FOR PERIODIC INTRODUCTION OF ELECTRONS INTO AN ELECTRON ACCELERATOR

Rolf Wideröe, Zurich, Switzerland, assignor to Aktiengesellschaft Brown, Boveri & Cie, Baden, Switzerland, a joint-stock company

Application September 23, 1948, Serial No. 50,868
In Switzerland September 23, 1947

7 Claims. (Cl. 315—14)

1

This invention relates to devices for accelerating a stream of charged particles such as electrons and the like and more particularly to an improved circuit arrangement by which the electron stream is introduced into the device at the proper instant relative to the forces under which the stream is accelerated.

The circuit is especially suited to electron accelerators of the betatron type (these are also known as ray transformers) and will be described in its relation thereto. In the betatron type of accelerator, where electron acceleration takes place along a circular orbit in an evacuated toroidal tube under the combined action of inducing and guiding magnetic fields, satisfactory operation requires the electron stream to be introduced periodically into the tube from an electron injector or "gun" at or near the instant when the magnetic field starts to build up from its zero value. Also it is advantageous to place the cathode of the injector under voltage only for a very brief instant so that electron injection will be equally as brief.

For synchronizing electron injection with the magnetic field of the device, it has been found desirable to control the starting of the cathode voltage from the energizing current for the magnetic field winding. One practical method has been to insert a saturated current transformer in the energizing circuit of the electron accelerator, with the primary being connected in series with the field winding or in series with the condensers delivering the excitation current of the field winding. Because the current in the secondary winding of the current transformer is very small the magnetization of said peaking transformers will rise from zero to its maximum saturation value in a very short time after the current flowing through its primary winding passes through its zero value. This produces a brief peaked voltage in the transformer secondary which voltage can be used itself to directly excite the cathode of the electron injector or indirectly by applying the same to trigger the control grid of a tube such as a thyratron, high vacuum triode or the like whose plate-cathode elements are connected in circuit with the injector cathode. In either case, it is essential that the voltage peak rise most rapidly, i. e. within a few microseconds and at the correct instant relative to the main magnetic field of the electron accelerator.

The present invention also makes use of a peaking transformer type of control circuit for energizing the cathode of the electron injector and has for its primary object the provision of a novel arrangement by which the starting instant of the voltage applied to the cathode of the electron injector can be finely adjusted as may be required to obtain the desired exact coinci-

2

dence between electron injection and the magnetic field of the accelerator which varies periodically between zero and maximum values.

In particular, the desired result is attained by means of an additional current passed through the peaking transformer, the added current being displaced about 90° in phase relative to the current which energizes the magnetic field producing winding of the accelerator, and the impedance of the circuit which carries the additional current being so great that the inphase-current flowing in this parallel connected circuit has practically no adverse effect upon the voltage produced by the peaking current transformer.

Several practical embodiments of the new control circuit are illustrated in the accompanying drawings. Fig. 1, a view in vertical central section through an induction type electron accelerator of conventional construction, shows one arrangement where the secondary of the peaking transformer is connected directly to the cathode element of the electron injector from which streams of electrons are introduced into the annular chamber to be accelerated; Fig. 2 illustrates in a more schematic manner a modification of the Fig. 1 circuit in which the additional current applied to the peaking transformer is obtained from a voltage source displaced 90° in phase relative to the voltage which energizes the field winding of the accelerator rather than from the latter as is done in Fig. 1, and Fig. 3 also a schematic view illustrates still another modified embodiment in which the voltage produced at the peaking transformer is used to trigger thyratron valves which in turn switch the cathode of the electron injector in and out relative to its energizing voltage.

Referring now to the structure and circuit shown in Fig. 1, numeral 1 designates the winding of the accelerator, for instance a betatron, which when energized produce the accelerating and guiding magnetic field components for the injected stream of electrons. A typical betatron accelerator comprises a magnetic field structure made up from vertically disposed steel laminations of appropriate contour which includes a pair of cylindrical poles 1a, 1b separated by an air gap 1c and located concentrically along axis x—x, and a pair of mutually confronting annular guide poles 1d, 1e separated by air gap 1f. Yoke members 1g complete the magnetic circuit for the time-varying magnetic flux set up in the annular and cylindrical poles, under the influence of which, an electron stream will be accelerated around and around the tube along orbit k. Poles 1a, 1b and 1d, 1e are surrounded by the annular winding 1 which is divided into upper and lower sections connected in series. An annular evacuated tube 1h, preferably of glass, rests in the

air gap $1f$ between the annular poles $1d$, i.e. The field winding 1 is connected to a source of periodically varying voltage u which is usually a sinusoidal wave in the power frequency range i. e. 50 cycles or so per second. A pair of condensers 2 for compensation of the magnetizing current from winding 1 and the primary 4 of the saturated peaking current transformer 3 are grouped in series, and this series group is connected in parallel with the winding 1 . The electron injector located within tube $1h$ is comprised of an electron emissive cathode 6 connected across the secondary 5 of transformer 3 and an anode 7 . A target anode $1j$ within the tube is struck by the electron stream emitted from cathode 6 after the stream has been fully accelerated on its orbit k .

If more detailed information is desired concerning the actual construction of the winding 1 , the magnetic structure on which it is wound or the arrangement of the electron injector and evacuated tube etc., reference may be had to my co-pending application, Serial No. 720,544, filed January 7, 1947 and issued January 16, 1951 as Patent No. 2,538,718.

In accordance with the invention, the additional current by which the starting moment of the peaked voltage wave produced by transformer 3 can be shifted is supplied by a transformer 9 . The primary $9a$ of this transformer is connected across the voltage line u and the voltage produced by the secondary $9b$ is connected through an adjustable resistance 8 across the transformer primary 4 . Because of the fact that the field winding 1 possesses a highly inductive characteristic, its energizing current and hence the main current through primary winding 4 will lag almost 90° behind the applied voltage u . The additional current that flows through resistance 8 and transformer winding 4 and which is also derived from the same voltage source u will likewise be displaced in phase by about 90° relative to the energizing current for winding 1 and transformer winding 4 . Thus by adjusting the resistor 8 , the phase position of the resultant current flowing through transformer winding 4 and which determines the starting of the peaked voltage wave produced across the output terminals of the transformer secondary 5 can be very conveniently adjusted.

The amplitude of the peaked voltage wave is somewhat diminished by the additional current in phase with the current through the field winding 1 passed through the primary 4 because of the presence of the parallel connected resistor 8 . If C is chosen to represent the resulting capacity, i. e. the capacity of the windings plus the capacity of the connected circuit with the electron injector $6-7$, and L the inductance of transformer 3 (both values being referred to the winding 4 through which the additional current flows), the maximum value of the voltage peak becomes:

$$u = u_0 \left[1 + E k s p \left(-\frac{\pi}{2R} \sqrt{L/C} \frac{1}{\sqrt{1 - \frac{L}{4R^2C}}} \right) \right]$$

$$\sim u_0 \left[1 + E k s p \left(-\frac{\pi}{2R} \sqrt{L/C} \right) \right]$$

so long as the parallel resistance 8 (designated R in the above equation) is still large. As long as this parallel resistance

$$R \geq \sqrt{\frac{L}{C}}$$

the voltage peak will attain at least 58% of its maximum value; such mathematical relationship therefore constitutes practically a minimum lower limit for the size of the parallel resistance R .

If desired, the additional current to be applied to the primary of the peaking transformer can be taken from a voltage source that is displaced 90° relative to the voltage used for energizing the field windings of the betatron. One such practical arrangement is shown in Fig. 2. Here, it will be observed that the winding 1 , transformer 3 and condensers 2 are connected in the same manner as in Fig. 1. For energizing winding 1 and producing the additional current to be applied to peaking transformer 3 , a three phase voltage supply source is utilized. The separate phases are indicated by terminal vectors R , S and T and these are star connected to a common voltage point O . Winding 1 is connected across terminals R and S , and transformer 10 which is to supply the additional current for peaking transformer 3 has its primary $10a$ connected across terminals $O-T$, the voltage across the latter being of course displaced 90° in phase relative to that across terminals $R-S$. The voltage across the secondary winding $10b$ is made adjustable and applied across the primary winding 4 with a choke coil 12 in the circuit. Operation of the Fig. 2 control is otherwise the same as in Fig. 1. So far as diminution of the voltage peak is concerned, the presence of choke coil 12 in parallel with winding 4 will cause a reduction in the amplitude of the voltage peak in the ratio of

$$\frac{L_{par}}{L + L_{par}}$$

where L is the inductance of transformer 3 and L_{par} is the inductance of choke coil 12 . The inductance of the latter should therefore preferably be at least five times that of the peaking transformer 3 to prevent too great a reduction in the peaked voltage.

In the Fig. 2 circuit, care should also be taken that the capacity of the coil 12 effective between the terminals is likewise connected in parallel to the capacity of the peaking transformer 3 , and, in order to keep the total capacity C small, the choke coil 12 must therefore be provided with a low-capacity type of winding of not too great a number of turns. The Fig. 2 circuit is preferable to the Fig. 1 arrangement in that the wattage losses for the additional current are less for coil 12 than for resistance 8 .

Also the wattless power in the choke will be small and can therefore be disregarded. Instead of a choke 12 to establish a current through transformer winding 4 which lags the current through winding 1 by 90° , a condenser could be used and thus establish a 90° leading current; but if this be done, the capacity of the condenser must be small in relation to the transformer capacity C to prevent a decreasing effect on the peak voltage, and for this reason, the required voltage across the condenser would have to be inconveniently high in order to produce the additional current required in the transformer primary 4 . Thus from practical considerations, the use of a choke coil producing the additional current at a 90° lag in phase relative to the magnetizing current of the accelerator is to be preferred in most cases.

Fig. 3 illustrates an embodiment of the invention wherein the voltage produced in the secondary winding of the peaking transformer is

used indirectly to effect brief energization of the cathode of the electron injector. In this form of the invention, the betatron (as described in more detail in my aforesaid application), is adapted to accelerate separate electron streams on both positive and negative halves of the alternating voltage wave u , the electron streams being injected into the tube alternately and in opposite directions at the beginning of each positive and negative energization of the field winding 1. Thus two electron injectors operating 180° apart in phase are provided and each has its own peaking transformer type of control. Referring now to Fig. 3, it will be seen that the winding 1 and condensers 2-2' are arranged as before. However, two peaking transformers 3 and 3' in series with condensers 2 are required, as well as two other transformers 9 and 9' which serve as the source of supply voltage for the additional current that is applied to the respective primary windings of the transformers 3 and 3'. Resistances 8 and 8', both adjustable, are inserted in the secondary circuits of transformers 9 and 9' to control the magnitude of the respective additional currents put through transformer primaries 4 and 4'. Operation of the Fig. 3 circuit thus far is the same as in Fig. 1 with the additional currents supplied by transformers 9 and 9' being displaced 90° in phase from the currents passed through the main field winding 1.

In the circuits shown in Figs. 1 and 2, the secondary of the peaking transformer is connected directly to the cathode of the electron injector. In Fig. 3, a modified arrangement is utilized, in which a thyratron type of tube connected in the circuit between the cathode of the electron injector and a source of voltage is triggered at the proper instant by the peaked voltage produced in the secondary of the peaking transformer. The energizing circuit for the cathode 6 of the electron injector producing electron stream 20 includes a diode rectifier 18 connected across condenser 2 through resistor 19, a thyratron tube 14, inductance 17 and condenser 16. The energizing circuit for cathode 6' of the electron injector producing electron stream 20' includes diode rectifier 18' connected across condenser 2' through resistor 19, thyratron tube 14', inductance 17 and condenser 16'. The grid circuit of thyratron 14 includes a fixed biasing voltage represented by battery 13 and the secondary 5 of peaking transformer 3; similarly the grid circuit of thyratron 14' includes battery 13' and the secondary 5' of peaking transformer 3'.

Operation of the Fig. 3 circuit is as follows:

When the voltage peak occurs in transformer secondary 5, thyratron 14 is triggered to a conductive condition thus connecting the voltage on condensers 2 and 2' through thyratron 14 and rectifier 18 to an oscillatory circuit comprised of condenser 16 and inductance 17. This effects a peaked voltage of brief duration on condenser 16, the voltage rising according to the equation

$$\sqrt{2u(1-\cos vt)}$$

where v is the frequency of the oscillatory circuit 16-17, u is the voltage applied to winding 1 and the losses are small. Such voltage is of course likewise applied to cathode 6 and produces the electron stream 20. Substantially 180° later in the wave of alternating voltage u , thyratron tube 14' is triggered thus connecting the voltage on condensers 2 and 2' through thyratron 14' and rectifier 18' to an oscillatory circuit composed of condenser 16' and inductance 17; and the peaked

voltage produced across condenser 16' is similarly impressed upon cathode 6' to produce the other and oppositely directed electron stream 20'. By adjusting the resistors 8 or 8', the voltage peaks produced by transformers 3 or 3' and hence the triggering instants of thyratrons 14, 14' can be advanced or retarded as may be desired to thereby adjust the instant of electron injection relative to the varying magnetic field produced by the winding 1.

10 In conclusion, it is to be understood that while the above described constructions represent preferred forms of the invention, still other changes and modifications are possible without departing from the spirit and scope of the appended claims. Thus for example, while the additional, adjustable out-of-phase current is illustrated as being applied directly to the primary winding 4 of the peaking transformer, such is not the only way of obtaining the desired result since the additional current could just as well be applied to a separate winding on the transformer core.

I claim:

1. In a device for accelerating charged particles such as electrons and the like to high velocity, an electron injector including an electron emissive cathode, means including a main winding for cyclically producing a time-varying magnetic field of such space distribution as to confine 25 the electrons emitted from said injector to a desired orbit while continuously accelerating them along such orbit, a peaking transformer for periodically producing in its secondary a peaked voltage effective to briefly energize said cathode 30 to thereby produce electron streams periodically, said transformer being provided with a primary winding which is magnetized by the current flowing through said main winding and means providing said transformer with an additional 35 magnetizing current phase-displaced relative to said first magnetizing current and impedance means in the circuit of said additional current of such a value that the peak voltage in the secondary of said transformer is not appreciably reduced by said additional current circuit.

2. A device for accelerating charged particles as defined in claim 1 wherein said transformer has but one primary winding and both of said magnetizing currents are applied to such winding.

3. A device for accelerating charged particles as defined in claim 1 wherein said additional current is produced by a voltage in phase with the voltage applied to said magnetizing winding of the accelerator and the additional current circuit includes an adjustable resistance.

4. A device for accelerating charged particles as defined in claim 1 wherein said additional current is produced by a voltage which is displaced in phase relative to the voltage applied to said magnetizing winding of the accelerator, and the additional current circuit includes a reactance.

5. A device for accelerating charged particles as defined in claim 4 wherein said reactance is mainly inductive in character.

6. A device for accelerating charged particles as defined in claim 1 wherein said cathode is connected directly to the secondary of said peaking transformer.

7. A device for accelerating charged particles as defined in claim 1 wherein the energizing circuit for said cathode includes a grid controlled tube for rendering said cathode circuit conductive and non-conductive, and the secondary of

said peaking transformer is connected in the grid circuit of said tube.
